Primary Examiner — John R Yeh(74) *Attorney, Agent, or Firm* — Hanley, Flight & Zimmerman, LLC(57) **CLAIM**

The ornamental design for a grill scaper, as shown and described.

DESCRIPTION

FIG. 1 is a left front perspective view of our design for a grill scaper;

FIG. 2 is a front view thereof, the rear view being a mirror image thereof;

FIG. 3 is a left side view thereof, the right side view being a mirror image thereof;

FIG. 4 is a top view thereof; and,

FIG. 5 is a bottom view thereof.

The broken lines in the figures depict portions of the grill scaper that form no part of the claimed design.
